Application October 17, 1935, Serial No. 45,388

10 Claims. (Cl. 179—171)

My invention relates to resonant networks in general and more particularly to those which provide a means for widening the transmission pass band of such networks under certain conditions.

It is now well known that the fidelity of reproduction in a radio receiving system may be greatly improved when local or strong signals are being received by widening the pass band of the system's resonant network. During the early stages of development of the radio art it was felt that the pass band must be relatively narrow in order to provide proper selectivity for the system. Although this use of a narrow pass band did provide greater selectivity, it had the disadvantage that currents having certain desired frequencies were strongly attenuated in their transmission through the coupled circuits of the resonant network. It has been conclusively shown, however, that sufficient selectivity may be obtained when local or strong signals are being received by a relatively wider pass band. This wider pass band permits a larger group of side band frequencies to be transmitted through the system.

One of the methods of effecting a widening of the pass band is by symmetrically detuning two coupled oscillatory circuits of the resonant network. That is to say, the resonant frequency of one coupled circuit is lowered while the resonant frequency of the other circuit is raised an equal and opposite amount.

It is an object of my invention to provide an improved method of symmetrically detuning a pair of coupled oscillatory circuits in a resonant network.

It is a further object of my invention to provide an improved means for symmetrically detuning two coupled oscillatory circuits by means all of whose component parts are stationary with respect to each other.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which Figs. 1, 2 and 3 represent different embodiments of my invention. Fig. 4 is a chart illustrating the region of maximum selectivity, the expanding and contracting region and the high fidelity region of the circuits illustrated in Figs. 1, 2 and 3. Fig. 5 is a vector diagram il-

lustrating the operating characteristics of the equivalent capacity network of Fig. 3.

Referring to Fig. 1, it will be seen that the upper portion of the figure represents a conventional super-heterodyne radio receiving system which includes an aerial or pick-up device 1, a radio frequency amplifier stage 2, a detector and oscillator stage 3, a stage of intermediate frequency amplification 4, a second detector and automatic volume control stage 5, an audio frequency amplifier stage 6 and a loud-speaker 7. Only those portions of the radio receiving system to which my invention forms an integral part have been shown in detail.

The first detector stage 3 is coupled to an amplifier 8 of the electron discharge type through the coupling transformer 9. Condensers 10 and 11 are connected across the primary and secondary windings 12 and 13 respectively of the coupling transformer 9 and are adjusted to tune the windings 12 and 13 to the intermediate frequency. By-pass condensers 14 and 15 connect the lower side of windings 12 and 13 to ground in the customary manner. Amplifier 8 is illustrated as being an electron discharge device having a cathode 16 which is maintained at the desired potential by a self-biasing resistor 17. A by-pass condenser 18 is placed across the self-biasing resistor 17 and is connected to ground in the well known manner. Amplifier 8 is also provided with a control grid 19, a screen grid 20 and an anode 21. The output of the electron discharge device 8 is fed to a diode detector 22 through the coupling transformer 23. The primary winding 24 of transformer 23 is provided with a condenser 25 which tunes this winding to the intermediate frequency. One side of the secondary winding 26 of transformer 23 is connected to the anode 27 of the diode 22 while the other side of winding 26 is connected through a potentiometer 28 to the cathode 29 of diode 22. A by-pass condenser 30 is placed across potentiometer 28. The audio frequency amplifier stage 6 is fed from the potentiometer 28 through the movable contact 31. Potentiometer 28 also provides automatic volume control in a manner well known in the art through conductor 32.

In the application of my invention to the radio receiving system hereinbefore described advantage is taken of the fact that the input capacitance of a three element electron discharge amplifier may be considered as the grid to cathode capacitance plus the voltage amplification of the electron discharge device multiplied by the grid to plate capacitance. Thus by properly choosing

the impedance in the output circuit of the electron discharge device, the input side of the device may reflect substantially pure undamped capacitance. As the voltage amplification of the triode is varied in accordance with its grid bias, the capacitance reflected in the grid circuit is also varied in accordance therewith. Since the necessary value of capacity required to detune a pair of coupled oscillatory circuits is small, the triode may be used of this purpose by connecting the grid and cathode in the oscillatory circuit.

In the receiving system of Fig. 1, the control grid 51 of the electron discharge device 52 is connected to the upper side of winding 12 of transformer 9 through the condenser 53. The cathode 54 of electron discharge device 52 is connected to ground through the self-biasing resistor 55 and a by-pass condenser 56. The anode 57 of discharge device 52 is connected through a resistor 58 and an inductance 59 to the high potential source (indicated as B+). The magnitude of the capacitive reactance reflected in the input circuit of the electron discharge device 52 is a function of the resistance 58 and the inductance 59 in the anode circuit. The grid 62 of a similar electron discharge device 60 having a cathode 61 and an anode 63 is connected to the upper side of the winding 13 of coupling transformer 9 through condenser 64. The biasing resistor 55 and by-pass condenser 56, which provide a suitable potential on the cathode 54 of electron discharge device 52 also provide a suitable potential on cathode 61 of electron discharge device 60. It will be understood that with electron discharge devices 52 and 60 connected as thus described in the circuit of the intermediate frequency stage 4, condensers 10 and 11 must be so adjusted that the coils 12 and 13 are tuned to the intermediate frequency.

The oscillatory circuits associated with windings 12 and 13 may now be symmetrically detuned by decreasing the negative bias on the control grid 51 of electron discharge device 52 and by increasing the negative bias on the control grid 62 of electron discharge device 60. This causes an increase in the voltage amplification of device 52 and a decrease in the voltage amplification of device 60 which in turn causes the reflected input capacity of the device 52 to increase and the reflected input capacity of device 60 to decrease.

The symmetrical detuning operation may be made completely automatic by providing a separate intermediate frequency channel. This separate channel which will hereinafter be termed the fidelity control channel is coupled to the main intermediate frequency channel 4 through condenser 33. The electron discharge device 34, having a cathode 35, a control grid 36, a screen grid 37 and an anode 38, operates in a manner similar to the electron discharge device 8. It has, however, one important difference from the electron discharge device 8 in that the cathode 35 is provided with an adjustable self-biasing resistor 39 in the place of the ordinary fixed self-biasing resistor. The active portion of the resistor 39 is provided with a by-pass condenser 40. The output of the electron discharge device 34 is fed to a diode 41 through a coupling transformer 42 and is preferably adjusted so that its primary windings 43 and 44 are critically coupled. Condensers 45 and 46 tune the primary winding 43 and the secondary winding 44 respectively to the intermediate frequency. By critically coupling windings 43 and 44 the fidelity channel becomes extremely selective and passes only a narrow band

of frequencies closely adjacent to the intermediate frequency. This has the advantage of forcing the operator to tune the receiving system to the center of the signal. One side of the secondary winding 44 is connected to the anode 41 of the diode 41 while the other side is connected to the cathode 48 of the diode 41 through the potentiometer 49. A by-pass condenser 50 is shunted across potentiometer 49.

The control grid 51 of the electron discharge device 52 is connected to the cathode 48 of diode 41 through a resistor 65 and a conductor 68. The control grid 62 of the electron discharge device 60 is connected to a movable contact 66 on potentiometer 49 through resistor 67 and conductor 68. By connecting a resistor 70 between conductors 68 and 69 and grounding the mid-point, the grid bias of one triode increases as the grid bias of the other triode decreases. By-pass condensers 71 and 72 are connected across resistor 70 in the manner shown.

In order to overcome the negative bias on control grid 36 of the electron discharge device 34 so that current will flow in the output circuit when a signal is being received having greater than a predetermined intensity, control grid 36 is also connected through a resistor 73 to a diode 74. The diode 74 is so connected that a positive unidirectional voltage is applied to control grid 36 when a signal is being received. Thus anode 75 of diode 74 is grounded and a resistor 76 is connected between anode 75 and cathode 77 of diode 74. A condenser 78 connects cathode 77 to the anode circuit of electron discharge device 8. Since the cathode of diode 74 becomes positive by an amount which is a function of signal level, it will be understood that the grid bias on electron discharge device 34 varies as a function of carrier intensity. Now since the potential level of the cathode 35 with respect to the control grid 36 may be varied by shifting the movable contact 79 on resistor 39, it is obvious that movable contact 79 is in effect a sensitivity control for it determines the signal intensity level at which the fidelity control channel becomes operative. Since the unidirectional voltage swing on the grids 51 and 62 is limited by the position of the contact 66 on potentiometer 49, contact 66 may properly be termed a tone control for its position determines the maximum width of band expansion.

The operation of the receiving system is as follows: An incoming high frequency signal is received on the pick-up device 1, is amplified in the radio frequency stage 2 and is changed to an intermediate frequency in the first detector and oscillator stage 3. The signal is transmitted from stage 3 through the coupling transformer 9 to the intermediate frequency amplifier 8. After being amplified by device 8, the signal is transmitted through the coupling transformer 23 to the second detector 22, where it is demodulated to reproduce the transmitted audio wave. The audio frequency is amplified in the audio frequency stage 6 and the electrical signal is finally emitted as a sound wave through the loud-speaker 7.

If the intensity of the incoming signal is above a predetermined value as determined by the setting of movable contact 79, an intermediate frequency wave is amplified by electron discharge device 34 and is supplied to the diode 41 of the fidelity control channel. As the current begins to flow in the diode 41, the unidirectional voltage applied to the control grid 51 becomes less negative and the unidirectional control voltage

applied to control grid 62 becomes more negative. This increase in the amplification of discharge device 52 causes capacitance to be added to the oscillatory circuit associated with winding 12 of coupling transformer 9. The decrease in the amplification of discharge device 60 causes capacitance to be removed from the oscillatory circuit associated with winding 13 of coupling transformer 9. This causes one of the two coupled circuits to be detuned from the intermediate frequency in one direction while the other circuit is detuned an equal amount in the opposite direction.

The extent of detuning is determined by the position of movable contact 66. The particular signal intensity value, however, at which the detuning operation begins is determined by the position of contact 79. The reason for this is that as soon as the bias on control grid 36 is reduced to substantially zero the grid 36 begins to draw current and any further increase in potential across resistor 76 due to a further increase in carrier intensity produces a voltage drop across resistor 73 due to grid current flowing therein. This voltage drop is, of course, of opposite polarity to that on resistor 76 and thus opposes further change in the grid voltage in a positive direction. Hence, the voltage on grid 36 remains substantially constant for values of received signal intensity greater than that at which the voltage on resistor 76 equals that on the portion of resistor 39 to the left of contact 79.

If the incoming signal should for any reason fade so that its intensity level is below the predetermined value for which the position of contact 79 is adjusted, the discharge device 34 ceases to supply intermediate frequency to the diode 41 and the triodes 52 and 60 resume their normal value of amplification and, as a consequence thereof, the oscillatory circuits are again tuned to the intermediate frequency.

The automatic fidelity control means operation may be more readily understood by reference to Fig. 4 in which the principal curve F shows the relative output intensity from the fidelity control channel plotted as ordinates against received signal intensity plotted as abscissa. From points A to B, the signal strength is not sufficient to overcome the bias on discharge device 34 which is determined by the movable contact 79 and the fidelity control channel is, therefore, in an inoperative condition. For this reason, the range of signal strength from A to B may be termed the region of maximum selectivity. From B to C the signal strength is just sufficient to cause intermediate frequency current to flow in the fidelity control channel but the signal strength is not sufficient to cause full expansion of the pass band. From C on, no further increase in signal intensity will cause a further widening of the pass band and this region may be termed the high fidelity region with band fully expanded. Curve M indicates the shape of the transmission resonant curve for the region of maximum selectivity. Curve N indicates the characteristic double peak transmission curve when the band is fully expanded.

A different means for effecting symmetrical detuning without the use of moving parts is shown in Fig. 2. In this modification symmetrical detuning is brought about through the use of an electron beam tube whose electron stream path may be varied as a function of signal intensity. Those portions of the radio receiving system which are similar to the system described in Fig.

1 have been given the same reference numerals and only those portions which differ from Fig. 1 will be described in detail. In order to simplify the drawings, the second detector stage which is shown in detail in Fig. 1 is now represented generally as 5. It is, of course, obvious that an additional amplifying device may be used in the intermediate frequency stage and such a device is indicated generally as 4'.

To the ordinary radio receiving circuit are added two small condensers of equal value 80 and 81. One side of condenser 80 is connected to the upper side of winding 12 of coupling transformer 9 while one side of condenser 81 is connected to the upper side of winding 13 of coupling transformer 9. The lower sides of condensers 80 and 81 are connected to collector plates 82 and 83 respectively of an electron beam discharge device 84. Electron discharge device 84 is also provided with an electron emitting element 85 and two deflector plates 86 and 87. Plates 82 and 83 are provided with a suitable positive bias by being connected through resistors 96 and 97 respectively to the high voltage source (indicated as B+). The cathode or electron emitting element 85 is connected through a by-pass condenser 88 and a self-biasing resistor 87' to ground. It will be understood that so long as the stream of electrons emitted from cathode 85 are striking collector plate 82 and not collector plate 83, condenser 80 will be connected across the oscillatory circuit associated with winding 12 while condenser 81 will be merely floating across the circuit since no current path is provided from collector plate 83 to cathode 85. With condenser 85 in the circuit and condenser 81 out of the circuit, condensers 10 and 11 are adjusted to tune the windings 12 and 13 to the intermediate frequency. If now the path of the electron stream in the electron beam discharge device 84 be changed so that substantially all of the electrons leaving cathode 85 strike collector plate 83 capacity will have been removed from across winding 12 but an equal value of capacity will have been added across winding 13. This causes a symmetrical detuning of the oscillatory circuits.

The path of the electron stream is determined by regulating the negative bias on deflector plates 86 and 87. Assuming for the moment that no bias is placed on deflector plates 86, deflector plate 87, due to the fact that its potential is negative with respect to the cathode, causes most of the electrons emitted from cathode 85 to strike collector plate 82. If a negative bias substantially greater than the bias on deflector plate 87 be placed on deflector plate 86, the stream of electrons will be deflected so that substantially all of them strike collector plate 83. It is obvious that as the stream of electrons is swung from one plate to the other both condenser 80 and condenser 81 effect their associated oscillatory circuits to some extent.

As is indicated in Fig. 2, a second pair of coupled oscillatory circuits may be symmetrically detuned at the same time by a second electron beam discharge device 88.

Discharge device 88 is provided with two collector plates 89 and 90, two deflector plates 91 and 92, and an electron emitting element or cathode 93. Two condensers 94 and 95 similar to condensers 80 and 81 are connected to the upper side of windings 24 and 25 respectively of coupling transformer 23. The opposite sides of condensers 94 and 95 are connected to collector plates 89 and 90 of discharge device 88. Cathode 93 is connected to ground through self-biasing resistor 87' and 75

by-pass condenser 86' which are common to both cathodes 85 and 93. Collector plates 89 and 90 are given a suitable positive bias by being connected through resistors 94 and 95 to the high voltage source (indicated as B+).

Since the detuning operation depends upon the magnitude of the negative bias placed on deflector plates 86 and 91, it will be seen that the operation may be made completely automatic by applying a unidirectional negative voltage thereto which is a function of the signal level. This may be done in a manner similar to that described in connection with Fig. 1. In this case, however, the intermediate frequency amplifier 34 is coupled to the main intermediate frequency channel through a coil 98, coupled, for example to coil 26. Coil 98 is tuned to the intermediate frequency by condenser 99. The cathode 35 of amplifier 34 is provided with a fixed self-biasing resistor 100 in the place of the variable resistor 39 of Fig. 1. Since it is not necessary to provide a simultaneously increasing and decreasing bias, no resistor with its midpoint grounded is used in conjunction with potentiometer 49. A single condenser 103 now takes the place of the two condensers 71 and 72. The fidelity control conductor 101 is connected to potentiometer 49 through resistor 102 and movable contact 66. Conductor 101 is connected to deflector plates 86 and 91 through resistors 104 and 105 respectively. Cathodes 85 and 93 are connected by conductor 101' to cathode 48 of diode 41. Since the signal intensity level at which the detuning operation begins depends upon the potential level of the cathodes 85 and 93 above ground, it is obvious that the point at which detuning begins will depend upon the position of the movable contact 106 on the self-biasing resistor 87'. The end of resistor 87' opposite to the grounded end is connected to the high voltage source (indicated as B+).

The operation of the radio receiving system of Fig. 2 is similar to the radio receiving system of Fig. 1 except for the portion of the circuit which causes the symmetrical detuning. In the system of Fig. 2 condensers 80 and 94 are actively in the oscillatory circuits associated with windings 12 and 24 respectively when the signal level is below the predetermined point as governed by the sensitivity control 106. Condensers 81 and 95 under these conditions are merely floating on their associated circuits. If now the signal intensity level rises above the predetermined value determined by contact 106, the negative bias on deflector plates 86 and 91 deflect the electron stream so that substantially all of the electrons emitted from the cathodes 85 and 93 strike collector plates 83 and 90 respectively. This removes condensers 80 and 94 from their associated oscillatory circuits and adds condensers 81 and 95 to their associated oscillatory circuits. The pass band is then in its fully expanded condition.

A third means for effecting symmetrical detuning without the use of moving parts is shown in Fig. 3. In this modification symmetrical detuning is brought about through the use of a pair of phase shifting networks, each network including an electron discharge device. For the purpose of simplicity of illustration only the intermediate frequency stage of the radio receiving system is shown. Those portions of the intermediate frequency stage which are similar to the system described in Fig. 1 have been given the same reference numerals.

Shunted across winding 12 of the intermediate frequency coupling transformer 9 is the plate cir-

cuit of electron discharge device 107. The anode 108 of the electron discharge device 107 is connected through a by-pass condenser 109 to the upper side of winding 12. The cathode 110 of electron discharge device 107 is connected through by-pass condensers 111 and 112 to the lower side of winding 12. Cathode 110 is provided with a self-biasing resistor 113 in the customary manner. If the current through the plate circuit of the electron discharge device 107 is caused to lead with respect to the applied voltage by approximately 90°, the discharge device 107 will be equivalent to a condenser.

The plate current in discharge device 107 may be caused to lead with respect to the applied voltage by approximately 90° by connecting a condenser 114 and a resistor 115 in series between the anode 108 and the cathode 110 and by connecting the control grid 116 of the discharge device 107 between condenser 114 and resistor 115. The reasons why this circuit operates as an equivalent capacity network may be more readily understood by referring to Fig. 5. The applied voltage may be represented by a vector E . The voltage across condenser 114 due to the influence of resistor 115 slightly lags voltage vector E as is indicated by E_c . The current through condenser 114 leads its voltage E_c by 90° and may be represented by a vector I_c . The voltage across resistor 115 is in phase with current vector I_c and may be represented by a vector E_R . E_R also represents the voltage E_g applied to the control grid 116. Since the plate current flowing in an electron discharge device is always in phase with the voltage on the control grid, the current in the plate circuit of discharge device 107 may be represented by a vector I_p . As may be seen, I_p is approximately 90° ahead of the applied voltage E and therefore discharge device 107 is equivalent to a condenser whose current flowing through it is I_p . Since the amount of capacitance which is shunted across winding 12 depends upon the lengths of the current vector I_p , it is obvious that the equivalent value of capacitance represented by discharge device 107 may be varied by regulating the value of unidirectional voltage applied to control grid 116.

The anode circuit of a second electron discharge device 117 is shunted across winding 13 of coupling transformer 9 in a manner similar to that of discharge device 107. Discharge device 117 is provided with an anode 118, a cathode 119 and a control grid 120. A condenser 121 and a resistor 122 are connected across the anode 118 and cathode 119. The control grid 120 is connected between condenser 121 and resistor 122 in order that the current flowing from anode 118 to cathode 119 will lead with respect to the applied voltage by approximately 90°. A self-biasing resistor 123 and a by-pass condenser 124 are connected to cathode 119 in the customary manner.

In order symmetrically to detune the oscillatory circuits associated with windings 12 and 13, it is only necessary that the negative bias on control grid 116 be decreased while the negative bias on control grid 120 be increased an equal and opposite amount. This may be accomplished automatically, by providing a separate fidelity channel as was done in the radio receiving systems described in connection with Figs. 1 and 2. In this case the separate fidelity channel is coupled to the main intermediate frequency channel through coil 125 which may be coupled, for example, to coil 13. Coil 125 is tuned to the in- 75

termediate frequency by condenser 126. Although the method of applying an increasing and a simultaneously decreasing bias shown in Fig. 1 may be employed in this modification, I have shown in Fig. 3 an alternative method which employs two diodes 127 and 128. In this case the coupling transformer 42 is provided with two secondary windings 129 and 130 which are tuned to the intermediate frequency by condensers 131 and 132. The upper side of winding 129 is connected to anode 13 of diode 127 while the lower side of winding 129 is connected to cathode 134 of diode 127 through a by-pass condenser 135 and a resistor 136 as is shown in the drawings. Cathode 134 is grounded and the unidirectional control voltage for control grid 120 is taken from the ungrounded side of resistor 136. The upper side of winding 130 is connected to anode 137 of diode 128 while the lower side of winding 130 is grounded. Cathode 138 of diode 128 is provided with a self-biasing resistor 139 and a by-pass condenser 140 in the customary manner. The unidirectional control voltage for control grid 116 is taken from the cathode 138.

The operation of the symmetrical detuning circuit shown by Fig. 3 is as follows: Assuming that the intensity of the incoming signal is below the level at which it is desired to widen the pass band, condensers 10 and 11 are adjusted so that windings 12 and 13 are tuned to the intermediate frequency. The receiving system is now in its most selective condition as is indicated by curve M of Fig. 4. If the intensity level of the incoming signal now rises above the predetermined value corresponding to the value for which the system is adjusted for expansion of the transmission band, diode 128 causes the unidirectional negative voltage on control grid 116 to decrease and diode 127 causes the unidirectional negative voltage on control grid 120 to increase. This action causes the plate current flowing in discharge device 107 to increase which is equivalent to decreasing the capacitive reactance across winding 12. The plate current flowing in discharge device 117 is simultaneously decreased which is equivalent to adding capacitive reactance across winding 13. As a consequence thereof, the oscillatory circuits associated with windings 12 and 13 are symmetrically detuned.

If it is desired to detune the oscillatory circuits by changing the inductance rather than capacitance, an equivalent inductance network rather than an equivalent capacitance network may be used by simply reversing the position of condenser 114 and resistor 115 and by reversing condenser 121 and resistor 122 in the circuit shown in Fig. 3. This causes the current flowing through discharge devices 107 and 117 to lag approximately 90° with respect to the applied voltage. In other respects, however, the operation is exactly similar to that described for the circuit of Fig. 3.

Although in each of the radio receiving systems shown by Figs. 1, 2 and 3 a separate fidelity control channel is shown, it is obvious that automatic control may be obtained for the various detuning circuits by connecting the control elements thereof through suitable connections to the conventional automatic volume control bus, which is indicated, for example, at 32 in Fig. 1.

While I have shown particular embodiments of my invention it will of course be understood that I do not wish to be limited thereto since many modifications may be made both in the circuit arrangement and in the instrumentalities employed, and that I therefore contemplate by the appended

claims to cover all such modifications as fall within the true spirit and scope of my invention.

What I claim as new and desire to secure by Letters Patent of the United States is:

1. In combination, a pair of coupled oscillatory circuits, a plurality of electron discharge devices having their input circuits connected to said oscillatory circuits and their output circuits connected through a resistor to a source of high voltage, means, including means for varying the input capacitance of said electron discharge devices, for symmetrically detuning said oscillatory circuits. 5

2. In combination, a pair of coupled oscillatory circuits, an electron discharge device having its grid-cathode circuit connected across one of said oscillatory circuits and its anode connected through an impedance element to a source of high potential, a second electron discharge device having its grid cathode circuit connected across the other of said oscillatory circuits and having its anode connected through a second impedance element to a source of high potential and means for increasing the amplification of one of said discharge devices and simultaneously decreasing the amplification of the other of said discharge devices in response to the intensity level of the signal in said oscillatory circuits. 10

3. In a superheterodyne radio receiving system, the combination of a plurality of cascaded amplifiers including an amplifier operating at the intermediate frequency of said system, a pair of coupled oscillatory circuits tuned to said intermediate frequency, means for symmetrically detuning said circuits about said intermediate frequency, automatic means for actuating said detuning means when a signal is being received above a predetermined intensity, means for varying the intensity level at which said second mentioned means actuates said first mentioned means and means for limiting the effectiveness of said second mentioned means. 15

4. In a superheterodyne radio receiving system, the combination of a plurality of cascaded amplifiers including an amplifier operating at the intermediate frequency of said system, a pair of coupled oscillatory circuits, and means including an electron beam discharge device for symmetrically detuning said circuits about said intermediate frequency. 20

5. In a radio receiving system, the combination of a plurality of cascaded amplifiers and couplings between adjacent amplifiers, the couplings between one pair of adjacent amplifiers comprising a pair of oscillatory circuits tuned to the desired frequency, a capacitance element connected across one of said circuits, a second capacitance element connected across the other of said circuits, an electron beam discharge device having one collector plate and its cathode connected in the circuit of said first capacitance element and a second collector plate and its cathode connected in the circuit of said second capacitance element, and means for shifting the electron stream in said discharge device from one collector plate to the other. 25

6. In combination a pair of coupled oscillatory circuits, means for applying a signal voltage to one of said circuits, a plurality of electron discharge devices each having its output circuit connected across one of said circuits and having its input circuit controlled by said signal voltage, means for shifting the phase of the currents flowing through said discharge devices approximately 90° with respect to the applied voltage, 30

and means for varying the conductance of said discharge devices in response to the intensity of the signal in said coupled circuits.

7. In combination, a pair of coupled oscillatory circuits, means for applying a signal voltage to one of said circuits, a plurality of electron discharge devices each having its anode-cathode circuit connected across one of said circuits and having its grid cathode circuit connected to receive said signal, means for shifting the phase of the currents flowing through said discharge devices approximately 90° with respect to the applied voltage, and means for simultaneously increasing the conductance of one of said discharge devices while decreasing the conductance of the other of said discharge devices, thereby symmetrically to detune said circuits.

8. In a radio receiving system a pair of electron discharge devices and a coupling between adjacent discharge devices, said coupling comprising a pair of oscillatory circuits tuned to a desired frequency, electron discharge means for increasing the capacity of one oscillatory circuit and decreasing the capacity of the other oscillatory circuit in response to an increase in intensity of currents in said oscillatory circuits.

9. In a radio receiving system of the superheterodyne type, the combination of a plurality of

cascaded amplifiers including an amplifier operating at the intermediate frequency of said system, means for applying a signal voltage thereto, a pair of coupled oscillatory circuits tuned to said intermediate frequency, one of said circuits being connected with the output circuit of said intermediate frequency amplifier, a plurality of electron discharge devices each having its anode-cathode circuit connected across one of said oscillatory circuits and having its grid cathode circuit connected to receive said signal, means for shifting the phase of the anode current through said devices substantially 90° with respect to the applied voltage and means for increasing the mutual conductance of one of said discharge devices and decreasing the conductance of the other of said discharge devices.

10. In a radio receiving system a pair of electron discharge devices, a coupling therebetween comprising a pair of oscillatory circuits tuned to a desired frequency, and means all of whose component parts are fixed with respect to each other for increasing the capacity of one oscillatory circuit and simultaneously decreasing the capacity of the other oscillatory circuit in response to an increase in intensity of the currents in said oscillatory circuits.

JAMES E. BEGGS.

DISCLAIMER

2,156,076.—*James E. Beggs*. Schenectady, N. Y. AUTOMATIC FIDELITY CONTROL.
Patent dated April 25, 1939. Disclaimer filed September 17, 1940, by the
assignee, *General Electric Company*.

Hereby enters this disclaimer to claim 1 of said Letters Patent.
